Filed Oct. 27, 1972, Ser. No. 301,459

Term of patent 14 years

Int. Cl. D2—04

U.S. Cl. D2—268

FIG. 2

FIG. 1

FIG. 3

FIG. 4

FIG. 5

FIG. 6

FIG. 1 is a side elevational view of a shoe showing my new design;

FIG. 2 is a top plan view thereof;

FIG. 3 is a bottom plan view; and

FIG. 4 is an elevational view of the other side of FIG. 1.

FIG. 5 is a front view of the shoe; and

FIG. 6 is a rear view.

The characteristic feature of my design for a shoe resides in the combination of lateral, horizontal recessed periphery stitching with horizontal rope twist beading above the stitching, said combination extending around the base of the upper all as shown on the drawing.

I claim:

The ornamental design for shoe, as shown.
